UNITED STATES PATENT OFFICE.

CHARLES S. FREER, OF BROOKLYN, NEW YORK, ASSIGNOR TO EDWARD T. TODD & CO., OF NEW YORK, N. Y.

DESIGN FOR A PENCIL-CASE.

SPECIFICATION forming part of Design No. 21,572, dated May 24, 1892.

Application filed April 25, 1892. Serial No. 430,638. Term of patent 7 years.

To all whom it may concern:

Be it known that I, CHARLES S. FREER, a citizen of the United States, residing at Brooklyn, in the county of Kings and State of New York, have invented and produced a new and original Design for a Pencil-Case; and I do declare the following to be a full, clear, and exact description of the invention, such as will enable others skilled in the art to which it applies to make and use the same, reference being had to the accompanying drawing, and to the letters of reference marked thereon, which form part of this specification.

My invention relates to pencils; and its object is to produce a novel and attractive pencil-case.

The accompanying drawing is a side elevation of my newly-designed case, which comprises a tube A at one end, adjacent to which and in line therewith is a larger tube B. The third tube C comprises several sections $c c' c''$ of successively diminishing diameters, the

first section c , next to the tube B, being the largest of the sections and considerably larger than the tube B. An ornamental tip D, having one or more grooves d and the slit d' , forms the end of the case. The tubes are circular in cross-section, as indicated by the shading in the drawing, the transition from one tube to the next and from one section to another being by a more or less abrupt shoulder, as shown.

Having thus described my invention, what I claim, and desire to secure by Letters Patent, is—

The design for a pencil-case, as herein shown and described.

In testimony whereof I affix my signature in presence of two witnesses.

CHAS. S. FREER.
